SERVING TRAY SECTION

Willis A. Stageberg, Minneapolis, Minn., assignor to
Plastics Inc., St. Paul, Minn.

Filed Nov. 22, 1961, Ser. No. 67,657

Term of patent 14 years

(Cl. D44—10)

FIG. 1

FIG. 2

FIG. 3

FIG. 4

FIG. 5

FIG. 6

FIGURE 1 is a top plan view of a serving tray section showing my new design;

FIGURE 2 is a front elevational view;

FIGURE 3 is a bottom plan view;

FIGURE 4 is an end elevational view taken from the right of FIGURE 2;

FIGURE 5 is a rear elevational view; and

FIGURE 6 is an end elevational view taken from the left of FIGURE 2.

The serving tray section is shown mounted upon a broken line tray in FIGURE 1 for illustrative purposes.

I claim:

The ornamental design for a serving tray section, as shown and described.
